CHARLES H. FIELD, OF PROVIDENCE, RHODE ISLAND.

GRINDING HEAD.

Application filed January 5, 1927. Serial No. 159,130.

This invention relates to an improved construction of grinding head; and has for its object to provide a head-plate over which a sheet of abrasive material is tightly drawn by forcing a ring over the edge thereof to bind the edge of the material onto the periphery of the head-plate.

A further object of the invention is the provision of means in the head-plate for receiving the folds of the surplus portion of the edge of the abrasive sheet as it is turned back over the edge of the head-plate.

With these and other objects in view, the invention consists of certain novel features of construction, as will be more fully described, and particularly pointed out in the appended claims.

In the accompanying drawings:

Figure 1 shows a group of elements comprising the head-plate with a scalloped edge, beneath it a disc or sheet of abrasive material, beneath that the binding ring and beneath the whole is the tool for forcing the ring and sheet onto the head-plate.

Figure 2 shows the ring and disc positioned in the tool and the head-plate in position to be pressed downwardly to apply the sheet and ring thereto.

Figure 3 shows the head-plate as having been forced downwardly into the tool whereby the ring and sheet of abrasive material is forced thereonto.

Figure 4 shows the head-plate with the ring and abrasive sheet in position thereon.

Figure 5 is a perspective view showing the disc-shaped sheet of abrasive material flat.

Figure 6 shows the sheet of abrasive material as having been drawn up into dish form.

Figure 7 is an enlarged view showing a fragmental portion of one edge of the head-plate with the ring forced into position thereon and as binding the abrasive sheet onto the edge of the head-plate.

Figure 8 is a sectional view showing the scalloped edge on the head-plate and the abrasive sheet with its folds engaging the recesses of the scalloped edge.

Figure 9 is a view partly in section showing the tool as reversed side for side and the binding ring as resting on the tool in position to be driven off of the head-plate to release the abrasive sheet when it is desired to position a fresh sheet thereon.

It is found in the practical construction and operation of grinding heads of this character, in order to fold or draw the edges of a sheet of abrasive material over the peripheral edge of the head-plate, necessary to provide some space or spaces in the edge of the head-plate for the reception of the surplus or folds of the stock of the turned-back edge of the abrasive sheet so that the parts of the surplus edge will not overlap each other, which overlapping would prevent the binding ring from being forced thereover in a practical way. Therefore, to accomplish this in a simple and effective way, I have scalloped the flange or edge of the head-plate to receive the folds of the turned-back portion of the abrasive sheet when the ring is forced thereover. Also, I have provided a simple and effective tool for the assembling of the parts whereby it is only necessary to position the ring in the tool and the abrasive disc-shaped sheet over the ring and then by forcing the head-plate down into the tool the edge of the abrasive sheet is turned back over the edge of the head-plate and the ring is forced thereover, the folds of the surplus stock of the abrasive sheet being caused to extend into the scallops or spaces in the edge of the head formed to receive such surplus stock. Also, by the use of such improved applying tool, this tool may be reversed side for side and by placing the head-plate with its ring onto the tool, the ring will readily be driven from its binding position to release the abrasive sheet which is then readily removed and a fresh sheet of abrasive material positioned thereon; and the following is a detailed description of the present embodiment of my invention showing one means by which these advantageous results may be accomplished:

With reference to the drawings, 10 designates the head-plate of my improved grind-

ing head which is herein shown with a plain, flat, front face 11 having a relatively broad rearwardly-extending flange side face, or edge 12, the corners 13 of the plate being nicely rounded between the flange and the face plate. The flange or edge of the plate is provided with a plurality of spaced scallops, recess or spaces 14 into which the folds of the surplus stock of the turned-back edge of the abrasive sheet may extend so as to prevent them from overlapping each other and the plate is also provided with a rearwardly-extending hub 23, whereby it may be mounted upon a spindle 24 indicated in dotted lines to be rapidly rotated.

The sheet of abrasive material 15 is preferably first cut into disc form and in some instances is first drawn up into cup shape as best illustrated in Figure 6, by a separate process, the edge 16 and surplus stock on the edge 13 being taken up in scallop form, and in order to secure the turned-back edges of this abrasive disc on the edges or flanges of the head-plate, I have provided a binding ring 18, the inner diameter of which is just sufficient to fit tightly over the head plate when the abrasive sheet is folded over the edge thereof to bind the edge of the sheet onto the edge of the head-plate.

In order to facilitate the forcing of this ring over the edge of the head-plate to bind the abrasive sheet thereon, I have provided a ring-applying tool 19 which is provided with a shouldered recess 20 to receive the binding ring 18 and a shouldered recess 21 to receive and support the disc of abrasive material 15 above the ring.

The ring and the sheet being shown in position in the tool in Figure 2, and the head-plate being shown in position ready to be forced down into the ring.

Figure 3 shows the operation as having been completed and Figure 4 shows the grinding head removed from its tool with the abrasive material secured thereto by the ring 18.

In forcing this ring 18 onto the flange or edge of the head-plate 10, it will be best seen in Figures 7 and 8, that the surplus stock of the abrasive sheet is caused to take a scalloped form as at 16, this surplus stock naturally being caused to extend into the spaces 14 provided for it in the periphery of the head-plate.

This binding ring 18 serves while being forced into position to draw the abrasive sheet tightly over the working front face of the head-plate and holds it in that position while the head is rapidly rotated and the work is pressed against it to grind the same, and after the abrasive surface has been worn from the sheet, it is only necessary to drive this ring off and remove the sheet and replace it with a fresh one.

In order to drive this ring from its binding position, I simply reverse the tool 19 side for side, and the opening 22 in this tool is of sufficient size to permit the head to be forced therethrough but is of a size to retain the ring which is thus driven off to release the abrasive material.

My improved grinding head is very simple and practical in its construction and is effective in its operation and by its use I am enabled to apply a sheet or disc of abrasive material to the head and after the sheet has been used up it may be readily removed and replaced by a fresh one.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a grinding head, a head-plate having a front face and a side face, a dish-shaped member formed of an abrasive sheet with a wrinkled edge, a separate ring arranged to bind the wrinkled edge of said dish-shaped member on to the side face of said head, means being provided in said side face for receiving the folds of the wrinkled edge, and means on said head-plate whereby it may be mounted to be rapidly rotated.

2. A grinding head comprising a head-plate having a front face and rearwardly extending edge having scallops thereon, and a ring for binding the edge of an abrasive sheet on the periphery of said plate, said scallops in the edge receiving any folds in the edge of the sheet.

3. A grinding head comprising a head-plate having a peripheral edge portion an abrasive sheet stretched thereover, said periphery being recessed at spaced intervals to receive the folds of the surplus stock of the sheet when in engagement therewith, and a binding ring for drawing the sheet tightly over the face of the head-plate upon being forced into place for retaining the sheet firmly in position on said plate.

4. A grinding head comprising a head-plate having spaced recesses in its periphery an abrasive sheet stretched thereover and a ring binding the edge of the abrasive sheet onto the periphery of said head, said recesses serving to receive the folds of the surplus stock of the sheet.

5. A grinding head comprising a disc plate having a front face and a side face with a rounding connecting edge, said side face being provided with spaces or grooves arranged at intervals about its periphery, an abrasive sheet stretched over said plate with wrinkled margins, and a ring or band arranged to encircle said side face and bind the turned-back edge of an abrasive sheet

thereto, the wrinkled or crimped edge of the sheet being caused by pressure of the ring to enter said grooves.

6. In a grinding head, a disc plate-head having a side edge with spaced recesses therein, a disc-shaped member of abrasive material having a corrugated edge portion to be positioned on said head with the cor-

rugation with spaced recesses, and a ring arranged to fit over the corrugated edge ¹⁰ of the abrasive member to bind it to the side face of said disc plate.

In testimony whereof I affix my signature.

CHARLES H. FIELD.
